UNITED STATES PATENT OFFICE.

FRED ERNEST WIGGINS, OF MALDEN, MASSACHUSETTS, ASSIGNOR TO LUCIUS N. LITTAUER, OF GLOVERSVILLE, NEW YORK.

SEWING-MACHINE FOR SEWING OVERALL-STRAPS.

1,242,405.

Specification of Letters Patent.

Patented Oct. 9, 1917.

Application filed March 22, 1917. Serial No. 156,571.

To all whom it may concern:

Be it known that I, FRED ERNEST WIGGINS, a citizen of the United States, residing at Malden, in the county of Middlesex and 5 State of Massachusetts, have invented certain new and useful Improvements in Sewing-Machines for Sewing Overall-Straps, of which the following is a specification.

This invention relates to sewing machines, 10 the object thereof being to provide a simple and effective means for forming tapered suspender straps used in the manufacture of overalls, in which the edges are folded throughout their length and a reinforced lining piece stitched within the folds at one 15 end thereof.

Heretofore straps of this kind were made on a single needle machine, first folding one 20 edge of the strap and stitching it with the lining in place, then folding the opposite edge and completing the stitching, with the result that the straps were never uniform at the tapered portion, while the operation was slow and expensive. By means of the 25 present improvement, however, the formation of these straps is very much simplified.

In the drawings accompanying and forming part of this specification, Figure 1 is a 30 view of so much of a sewing machine as is necessary to illustrate my invention; Fig. 2 is a top plan partly sectional view showing the presser foot and folder for forming and feeding the straps. Fig. 3 is a perspective view of an arched presser foot; Fig. 4 is a 35 detail bottom view of the folded strap, with one edge partly flattened out to show the reinforced piece; Fig. 5 is a sectional view taken on line 5—5, Fig. 4, looking in the direction of the arrows; and Fig. 6 is a sectional view taken on line 6—6, Fig. 4, looking in the direction of the arrows.

Similar characters of reference indicate corresponding parts in the several figures of the drawings.

45 The sewing machine has a cloth plate 1, a looper shaft 2 carrying loopers 3, which may be of any of the well known kind used for single or double chain-stitch. The upper bearing 4 of the head carries a needle bar 5 provided with a needle holder 6 and needles 7. A presser bar 8 is also supported in the head and operates in the usual manner, it having a presser foot shank 9 secured thereto by a screw 10. This presser foot shank 9

has pivotally secured thereto by means of a 55 screw 11, a yoke 12, which is of arch form as at 13 and has a pair of depending portions 14, each carrying a presser foot 15 pivotally secured thereto as at 16 for rocking movement. Each presser foot is provided with 60 needle hole 17 for the passage of the needle 7. These presser feet coöperate with suitable feeding mechanism (not shown) which may be arranged to correspond with the feeding movement of the presser feet. Secured to the cloth plate by a bracket 20 and screws 21 is a folder 19. This folder is of arch form and comprises a body having spaced apart scrolls formed by bending the lower spaced edges of the body upwardly 70 and outwardly as at 24, and these bent edges of the body taper toward the delivery end of the folder. Secured on top of these bent portions 24 is a center piece or plate 22, having its edges curled as at 23 and terminating 75 in the upwardly and outwardly bent portions 24 of the folder body. The body is also provided with extending overhanging portions 26 overhanging the center piece or plate 22 and spaced apart to form a slot or 80 open space 27 from end to end of the folder, and forming the guiding channels 25 for the edges on the strip. This open space 27 from end to end of the folder permits the buckling of the strip without retarding or 85 interfering with the feeding action thereof through the folder at any time, as this space is not bridged by inwardly extending projections or portions. In the operation of the machine the end of the strip is placed on the 90 center plate 22, with the reinforcing lining 29 underneath. The end 30 of these two pieces may be folded under if desired to give a finished end. The strip 28 and lining 29 are then forced through the folder so that 95 the outer edges of the strip pass downward into the channels 25 and into the scrolls 24, which turn the edges thereof as it is fed up to the stitching position. The object of the open slot 27 is to enable the operator to feed 100 the strip sufficiently forward so that the presser feet and feeds will grasp the same and start it through the machine. The delivery end of the folder is made the width of the finished narrow end of the strap and 105 the spacing of the needles is also arranged to suit so that as the wider portions of the strip are fed through the folder, the center

of the strip, owing to its tapered form, will be caused to buckle and project upward into the open space 27 and this buckling of the surplus material exerts sufficient pressure on the edges of the strip as it passes through the folder to uniformly form the turned edges. To accommodate this surplus of material as it is buckled upward, is the reason for the provision of the yoked presser foot 10 with its arched formation.

From the foregoing it will be seen that in the manufacture of straps it is merely necessary for the operator to place the lining strips at the narrow end of the strap, fold 15 the end and place it in the folder, one strip under the other, thus reducing what has heretofore been a very expensive and tedious operation, to a simple and inexpensive one, while uniformity is assured and very rapid 20 production obtained.

I claim as my invention:

1. In a sewing machine for forming tapered suspender straps, the combination of an arch formed presser foot supporting 25 member, a pair of presser feet secured thereto, a folder having the delivery end thereof adjacent to the presser feet and comprising a body having a pair of spaced apart edges at its top and a pair of spaced apart scrolls 30 below said top and connected by a plate.

2. The combination described in claim 1, in which the scrolls are tapered toward the delivery end of the folder.

3. The combination described in claim 1, 35 in which the plate is located between the top and bottom of the folder.

4. The combination described in claim 1, in which the scrolls are tapered toward the delivery end of the folder and the plate is 40 located at the top of said scrolls.

5. The combination described in claims 1 and 4, in which the plate is located substantially midway between the top and bottom of the folder.

45 6. In a sewing machine, the combination of stitching mechanism, a pair of presser feet, a yoke formed member supporting said feet spaced apart, and means for buckling, turning and sewing simultaneously the two edges of a strip.

7. In a sewing machine, the combination of stitching mechanism, a pair of presser feet, a yoke-formed member supporting said feet spaced apart, means for guiding a pair 55 of strips one under the other, one forming a reinforcing strip, means for turning the two edges of one strip around the edges of the other and for buckling the strip, thereby to permit such turned edges to be sewed to 60 the reinforcing strip.

8. In a sewing machine, the combination of means for buckling a strip passing to the stitching mechanism, means for turning the edges of the strip, and means for stitching 65 the so turned edges of the strip.

9. In a sewing machine, the combination of means for buckling a strip passing to the stitching mechanism, means for turning both edges of the strip around the edges of a reinforcing strip, and means for stitching 70 such turned edges to said reinforcing strip.

10. The means specified in claim 8, in combination with presser foot mechanism effective to coöperate with both turned edges of a strip and permit the passage of a 75 buckled surplus portion of material.

11. The means specified in claim 9, in combination with presser foot mechanism effective to coöperate with both turned edges of a strip and permit the passage of a 80 buckled surplus portion of material.

12. In a sewing machine, the combination of folding mechanism effective to buckle and simultaneously turn and stitch both edges of a strip and effect the buckling of 85 the surplus portion of the strip, and means for stitching both edges of the strip simultaneously.

13. The combination described in claim 12, together with presser foot mechanism 90 coöoperating with said folder mechanism to permit the passage of the surplus material.

14. The combination described in claims 12 and 13, in which the presser foot mechanism comprises a pair of spaced apart 95 presser feet and an arch-formed supporting member.

15. In a sewing machine, the combination of folding mechanism and presser foot mechanism, the folding mechanism comprising 100 an arch-formed folder tapering toward its delivery end and having its upper edges spaced apart and having its lower edges also spaced apart and provided with scrolls, and a plate connecting the scrolls.

16. The combination described in claim 15, in which the presser foot mechanism also comprises an arch-formed supporting member and a pair of presser feet connected thereto.

17. A structure as specified in claims 15 and 16, in which the presser feet are connected to the arch-formed supporting member for rocking movement.

18. A folder comprising an arch-formed 115 body tapering toward its delivery end and having its upper edges spaced apart and its lower edges provided with a pair of spaced apart scrolls and a plate connecting said scrolls.

19. The folder described in claim 18, in which the plate is located at the top of the scrolls.

20. The folder described in claims 18 and 19, in which the plate is located substantially midway between the top and bottom of the folder.

21. A folder for a sewing machine comprising two similarly formed members spaced apart and located to taper toward 120

- each other at the delivery end of the folder, each of said members having its lower edge provided with a scroll and an overhanging upper edge and means for connecting said 5 similarly formed members.
22. The folder described in claim 21, in which the connecting means is in the form of a plate.
23. The folder described in claims 21 and 10 22, in which the plate extends over the top of the scrolls of said members and co-operates therewith to form the scroll.
24. The folder described in claim 21 in combination with stitching mechanism and 15 presser foot mechanism including a pair of presser feet spaced apart to correspond to the width of the work passage at the delivery end of the folder.
25. The combination described in claims 20 21 and 24, in which the spaced apart presser feet are carried by a yoke shaped support-
- ing member to which the presser feet are pivotally connected.
26. In a sewing machine, the combination of means for buckling a strip passing to the stitching mechanism without retarding or interfering with the feed movement of the strip as it passes to the stitching mechanism and comprising an arch-formed folder having its upper edges unbridged, and spaced 25 apart from end to end of the folder, means for turning the edges of the strip, and means for stitching the so turned edges of the strip. 30
- Signed at Boston, county of Suffolk, and 35 State of Massachusetts this 14th day of March, one thousand nine hundred and seventeen.
